**WARP THREADS SHEDDING OPERATION DEVICE
COMBINED WITH THE WEFT THREADS CARRY-
ING DEVICE FOR CIRCULAR WEAVING LOOMS****Giusto Casati, Barzano, and Carlo Cazzaniga,
Monticello, Italy****Application July 3, 1951, Serial No. 234,995****Claims priority, application Italy April 28, 1951****12 Claims. (Cl. 139—16)**

The present invention relates to a circular weaving loom and more particularly to a circular weaving loom having a warp threads shedding device combined with a weft thread carrying device.

One object of the present invention is to displace the warp threads during the weaving operation as little as possible.

An additional object of the present invention is to support the displaced warp threads properly during the weaving operation.

A further object of the present invention is to form the device in such a way that the warp threads can be easily inserted.

It is yet another object of the present invention to provide for a loom stopping mechanism in case one of the warp threads is broken during the weaving operation.

It is still another object of the present invention to increase the shed gradually during the weaving operation.

With the above objects in view, the present invention mainly consists in a circular weaving loom comprising a plurality of healds or heddles to effect guiding and shedding of the warp threads, a box wherein said healds are annularly arranged in groups, a warp shedding device formed by a plurality of moving members which are mounted to rotate at the rear part of said healds so as to exert a pressure thereon to push them forwardly, a warp stop motion means connected to the shedding device for turning movement therewith and including a feeler formed by a bar and by an arm to which the bar is secured, the bar being formed with a threaded hole, a screw threadedly engaging the bar in the hole and formed with an axial bore, a rode extending through the bore, a roller loosely mounted on the rod and positioned so as to engage the rear ends of the healds, the roller having a height which enables it to engage all heald groups, a helical spring wound around the rod, a pin on the rod, a lever engaged by the pin and turnable on the bar of the feeler, the lever being adapted to close an electric loom stopping circuit, a second spring also wound around the rod and exerting a pressure on the pin and thus on the lever to maintain the roller against the healds, and a weft spool carrying device including a weft carrying carriage, a bent needle having a V-shaped cross section tapering toward the lower end of the needle to effect the guiding of the weft thread, and a shed spreader means for moving warp threads from an inner to an outer position at which the picking is effected.

The weft carrying carriage of the loom comprises a framework of magnetic material, two brackets mounted on the framework, two spindles mounted on the brackets so as to be able to rotate in their supports, two equal wheels of magnetic material keyed on the spindles, two equal toothed wheels mounted on the spindles, an electromagnetic roller able to support and to attract the carriage, a smaller wheel of magnetic material rotatably mounted on its spindle and positioned in the upper part of the carriage in order to face the electromagnetic roller, an upper bow and a lower bow, both designed to be

2

wedged between the warp threads and precisely the upper bow in advance in respect to the lower bow, in the movement direction, so that the lower bow may be wedged in only after the gradual increasing of the shed.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings, in which:

Fig. 1 is a diagrammatic perspective view showing the overall construction of the loom;

Fig. 2 is a partly sectioned top view of Fig. 1;

Fig. 3 is a partly sectioned perspective view showing details of the construction in the upper part of the weaving loom to an enlarged scale;

Fig. 4 is a sectioned side view similar to Fig. 3 showing a modified construction;

Fig. 5 is a partial top view showing healds or heddles in displaced position;

Fig. 6 is a partial top view similar to Fig. 5 showing a modification;

Fig. 7 is a partial top view of the device showing a modification of the warp shedding device and the loom stopping mechanism;

Fig. 8 is a left-hand side view of the weft spool carrying device;

Fig. 9 is a top view of the weft spool carrying device;

Fig. 10 is a partial right-hand side view of the weft spool carrying device;

Fig. 11 is an overall partly sectioned front view of the circular weaving loom;

Fig. 12 is a partial top view of the device showing one position of the weft spool carrying device in the relation to the healds or heddles during the weaving operation; and

Figs. 13 to 15 are top views similar to Fig. 12 showing consecutive positions of the weft spool carrying device in relation to the healds.

Referring now to the drawings, and more particularly to Figs. 1 and 11 of the same, the weaving loom according to the present invention comprises a mechanism for the initial shedding motion of the warp threads *f. o.*

located at the upper part of the loom. This mechanism mainly consists in an annular hollow box A in which the healds or heddles M are mounted for a sliding motion in radial direction. A plurality of discs are arranged inside the box A for moving the healds M. The loom comprises further a weft spool carrying device consisting of a weft carrying carriage C and shed opener means E arranged on both sides of the weft carrying carriage C. Further provided are means for propelling the weft spool carrying device and a loom stop mechanism which acts in case of a warp thread breakage. This stop mechanism is shown in Fig. 7.

The mechanism causing the initial shedding motion of the warp threads will now be described in further detail. The annular hollow box A is mounted by means of a plurality of radial arms *a* on the hollow drive shaft B for rotation with the same around the shaft axis. The box A (Fig. 11) has an annular top wall 3 to which the free ends of the radial arms *a* are attached, for instance by screws, an annular bottom wall 4, a cylindrical outer wall 1 and an inner wall 2 concentric with the outer wall 1.

The four walls are connected together in any convenient manner for instance by screws (not shown) or by welding to form a substantially dust tight box, which may be filled with lubricating material. The outer wall 1 and the inner wall 2 are provided with a plurality of guide holes *h* (Fig. 3) which are respectively aligned in radial direction in the outer wall 1 and the inner wall 2.

2 for guiding the rear part **5** of the healds or heddles **M** for sliding movement in radial direction. The guide holes **h** are arranged in planes parallel to the top wall **3** and the bottom wall **4**, which planes are spaced equally from each other. The guide holes **h** in consecutive planes are displaced in circumferential direction by equal distances approximately equal to the maximum width of the healds or heddles **M**. The warp threads *f. o.* guided by healds **M** are, by this arrangement, evenly distributed around the circumference of the weaving loom as can be clearly seen from Fig. 1. Each of the healds or heddles **M** consists of a rear part **5** guided in the guide openings **h** of the annular box **A** and this rear part has a cross section slightly smaller than the cross section of the guide openings **h** so that the healds **M** can slide freely within the guide openings. A rectangular cross section is preferred for the rear parts **5** of the healds **M**, but any other cross section preventing turning of the healds **M** in their guide openings may be used. The front part **6** of the healds **M** is provided with an elongated eyelet **7**, best shown in Figs. 3 and 5, through which the warp threads *f. o.* are threaded. The rear part **5** of each heald **M** extends rearwardly beyond the inner wall **2** and the free ends of the healds **M**, when the healds are in rest position, are aligned on a circle concentric with the inner wall **2**, as clearly shown in Fig. 5. For the exact alignment of the rear ends of the healds **M** the rear part **5** of each heald is preferably formed with an annular boss **9** which abuts in the rest position of the healds **M** against the inner face of the inner wall **2** and is pressed against this inner face by a spring **8** surrounding the healds **M** and inserted between the bosses **9** of the same and the inner face of the outer wall **1** (Fig. 4). Arranged rearwardly of the free ends of the rear portions **5** of the healds **M** and within the member **A** are five discs **10**, **10'**, **10'', 10'''** and **10^{IV}**. These discs are equally spaced from each other and mounted on a shaft parallel to the main shaft **B**. This shaft is mounted for free rotation on two arms **11**, **12** (Figs. 3 and 11) which arms are in turn fastened to a sleeve member **G** which is concentrically arranged about the main shaft **B**. The member **G** is rotated about this main shaft in the direction of the arrow **R** (Figs. 12-15) at a greater number of R. P. M. than the main shaft by means of a pinion **I** (Fig. 11) meshing with an internal gear integrally formed with the member **G**. The spacing between the discs **10**, **10'**, **10'', 10'''**, **10^{IV}** is twice the spacing between the planes in which the healds **M** are arranged and the discs respectively engage the inner free ends of the healds **M** so that the healds arranged in every second of the above mentioned parallel planes are engaged and moved in outward direction as the discs rotate in the direction of the arrow **R** about the central axis of the loom. By this displacement of the healds **M** the initial shedding **b** is obtained as shown in Fig. 3. After a disc leaves a heald **M**, the latter is returned to its initial rest position by the spring **8**. The spring may also be omitted and in this case the heald **M** is returned to its rest position by the increased tension of the displaced warp thread or the discs may be magnetized so that they pull the healds **M** back to the rest position as they leave the free ends of the healds.

Instead of forming the outer portion **6** of the healds with an eyelet as described above the outer portion may be formed with a thin blade **7'** as shown in Fig. 6. In this case the warp threads *f. o.* are guided between consecutive side faces **7''** of the blades **7'** and they are displaced outwardly by the inclined faces **7'''** when the respective heald is displaced as described above. With this arrangement the warp threads have not to be threaded through eyelets in the healds which greatly simplifies the operation of the loom.

Instead of using round discs as shown in Figs. 3 and 11 star-shaped discs **10b** may be provided, having a plurality of radially arranged arms **10a** formed thereon

which engage the free inner ends of the healds **M**. Each of these discs instead of being free to rotate on their spindle may also be driven so as to roll its star-shaped surface on the free inner ends of the healds **M** and thus exert a push in a predetermined sequence. Such an arrangement is shown in Fig. 7 in which only the uppermost of the star-shaped discs is shown, whereby it is to be understood that a plurality of discs are provided spaced and mounted in a similar manner as the discs shown in Fig. 11.

Fig. 7 shows also the warp stop motion means, that is the mechanism for stopping the loom in case of warp thread breakage. This stopping device consists of an arm **13** extending in lateral direction from the arm **11**. This arm **13** is provided near its free end with a threaded opening therethrough and a hollow screw **14** is threaded through this opening. A rod **15** passes through the hollow screw **14** and is guided therein for sliding motion. A roller **16** is pivotally mounted on one of the free ends of the rod **15** and engages the inner free ends of the healds **M**. The roller **16** has to be made long enough so that it will consecutively engage all healds **M** as the device is rotated about the main axis of the loom. A pin **19** extends from the rod **15** at the location between the hollow screw **14** and the roller **16**. This pin **19** engages in a slot formed at one end of a double-armed lever **20** which is pivotally mounted at **21** on the arm **13**. A coil spring **23** is wound around the rod **15** abutting with its ends, respectively, against screw **14** and the pin **19** and pushing the rod **15** and the roller **16** attached thereto against the free inner ends of the healds **M** and tending to push the healds **M** outwardly. These healds are held as mentioned before in their rest positions by the force of springs **8** or by the tension in the warp threads *f. o.* or respectively by a combination of these two forces and the force tending to push the rod **15** outwardly should not be greater than the combination of the above-mentioned forces. Only when one of the warp threads is broken and the forces preventing the outward movement of the rod **15** are thereby reduced, the rod **15** should be allowed to move in outward direction. For the exact adjustment of the force acting on the rod **15** in outward direction another coil spring **17** is provided which is wound about the other end of the rod **15** and abuts on one side against the other end of the screw **14** and on the other side against a nut **18** screwed on the free end of the rod **15**. By adjusting the nut **18** the force of the spring **17** can be varied to counterbalance the force of the spring **23** to a greater or lesser degree. The force of the spring **23**, on the other hand, can also be adjusted by adjusting the position of the hollow screw **14**. When due to the breakage of one of the warp threads *f. o.* the roller **16** can move forward under the action of the spring **23**, the double-armed lever will tilt about its pivot **21** and the rear end of this lever will abut against the stationary electrical contact **22** and close an electrical circuit which, in turn, will cause the stoppage of the drive motor of the loom.

Referring now to Figs. 8 to 15, the means for propelling the weft spool carrying device and the weft spool carrying device itself including the weft carrying carriage **C** and the means for opening the shed beyond the point obtained by the initial shedding device shall now be described in further detail.

The means for propelling the weft spool carrying device comprise a magnetic roller **24** keyed to shaft **26** which is turnably mounted on the arms **25** extending in radial direction from the sleeve member **G** (Fig. 11). The roller **24** will rotate about the axis of the main shaft of the loom in the direction of the arrow **R** together with the sleeve member **G**. A bevel gear **D** is fixedly mounted on the hollow shaft **B** and this bevel gear meshes with the smaller bevel gear **24'** fixedly mounted on the shaft **26** of the roller **24**. The roller **24** will therefore rotate about its own axis while the whole weft spool

carrying device rotates about the main axis of the loom. A thrust roller bearing *k* is conveniently provided between the upper face of the mounting boss of the bevel gear *D* and the lower face of the member *G* to reduce the friction between these two members which rotate, as mentioned before, at different speeds. A second roller *28* of a diameter smaller than the roller *24* is mounted for rotation on a shaft *29* which, in turn, is mounted on two arms *27* extending under an angle from the two arms *25*. The arrangement is made in such a way that the roller *28* will trail the roller *24* when the device is rotated in the direction of the arrow *R*.

The weft spool carrying device comprises the weft carrying carriage *C* which has a supporting plate or frame work *30* of magnetic material from which two brackets *31* and *31'* extend in a direction substantially normal to the plate *30*. These brackets and brackets *44* and *45*, respectively, support two spindles *32* and *33* for free rotation. Two wheels *34* and *35* of equal diameter and formed from magnetic material are keyed to the spindle *32* and *33*, respectively. Two rings *36* and *37* of non-magnetic material and having a width smaller than the width of the wheels *34* and *35* are respectively tightly fitted on these wheels so that they project slightly from the smooth surface of the wheels. The weft carrying carriage *C* comprises further a wheel *38* of a diameter smaller than the diameter of the two wheels *34* and *35*. This wheel *38* is also formed from magnetic material and is mounted for free rotation on its spindle *39* which in turn is mounted on a bracket *40* extending from the plate *30* near the bracket *31*. Wheel *38* is mounted in relation to the wheel *34* in such a way that the wheel *34* will trail the wheel *38* when the device is rotated in the direction of the arrow *R*. A toothed wheel *46* is keyed to the free end of the spindle *32* extending beyond the bracket *44* and this toothed wheel meshes with a pinion *48* which is keyed to spindle *50* and has a diameter slightly smaller than the wheel *46*. Keyed to the spindle *50* is also a pulley *52* and a belt is wound around this pulley and smaller pulleys *56* and *58* mounted for free rotation on stud shafts fixedly connected to the plate *30*.

A similar arrangement of gears, pulleys and belts is made on the lower part of the plate *30*. A toothed wheel *47* is keyed to the shaft *33* of the roller *35* and this toothed wheel meshes again with a pinion *49* of a slightly smaller diameter than the diameter of the wheel *47*. Pinion *49* is keyed to the shaft *51* mounted for rotation on the bracket *45*. Keyed to the shaft *51* is further the pulley *53* and a belt *55* is wound in form of a closed loop around this pulley *53* and smaller pulleys *57* and *59* mounted in the pair of smaller pulleys mounted for free rotation on stud shafts. Bow-shaped members *60*, *60'* are mounted on the plate *30* substantially perpendicular to the same and located respectively adjacent the belts *54* and *55*. The front ends of these bow-shaped members *60*, *60'* are pointed in the direction of rotation of the weft spool carrying device and are located on this device in such a way that the pointed ends will enter into the initial shed of the warp threads when the device is rotated about the main axis of the loom.

The weft carrying carriage *C* is further provided with an articulated joint *41* designed to receive the spool *42* for the weft thread. The weft thread leaves the spool over the curved needle *43* which has a V-shaped cross section and is tapered at its lower end and guides the weft thread during the weaving operation to the apex of the shed.

The device as described above will operate as follows: The weft carrying carriage *C* is placed against the magnetic roller *24* in such a way that the bow-shaped member *60* extends with the pointed end between the initial shed *b* as shown in Fig. 12. The small wheel *38* and the big wheels *34* and *35* will thereby be on one side of the nondisplaced warp threads *f. o.* and the rollers *24* and *28* will be located on the other side of the warp

threads. The wheels *34* and *35* will thereby be attracted by the magnetic rollers *24* and *28* and the two rings *36* and *37* formed from non-magnetic material and respectively mounted on the wheels *34* and *35* will prevent a close adherence of these wheels to the rollers *24* and *28*, respectively, so that the warp threads can easily glide between the wheels and the rollers. When the weft spool carrying device is propelled around the main axis of the machine by the means described above the roller *24* will rotate in the direction of the arrow *X* and the roller *28* in the same directions indicated by the arrow *X'*. The wheels *34* and *35* attracted to the roller *24* by magnetic induction will therefore rotate in the direction of the arrow *Y*. The pulleys *52* and *53* driven respectively over the pinions *46*, *48* and *47*, *49* will thereby rotate in the direction of the arrow *Z*. The belts *54* and *55* respectively wound over the pulleys *52* and *53* and the small pulleys associated therewith move therefore in the direction of the arrow *Z'*.

The warp thread is brought to the initial shed position by the healds *M* and the members associated therewith as described above permitting the weft carrying carriage *C* to be passed through the shed for effecting the picking whereby the warp threads are displaced further in radial direction by the bow-shaped members *60*, *60'*. There occurs no displacement of the warp threads in circumferential direction as the weft carrying carriage *C* is moved about the main axis in the direction of the arrow *R* whereas the rollers *24* and *28* and the wheels *34* and *35* rotate in a direction opposite to the direction *R* and the device is designed in such a way that the surface speed of these rollers and wheels is the same as the speed with which the whole device rotates about the main axis. The same holds true for the belts *54* and *55* which move also in a direction opposite to the direction indicated by the arrow *R* with a surface speed equal to the speed with which the carriage *C* is rotated.

The gradual displacement of the warp threads in radial direction is clearly shown in the Figs. 12 to 15 which illustrate consecutive steps in the weaving operation. As can be clearly seen from these figures, the displacement of the warp threads occurs very gradually so that these threads are stressed as little as possible during the weaving operation. The displaced warp threads are also properly supported during the displacement by the belts *54* and *55*.

The device for shedding of the warp threads *f. o.* operates in a similar way in the upper and the lower part of the weft spool carrying device. The only difference between the upper shedding device shown in Fig. 8 and the lower part illustrated in Fig. 10 is that the bow-shaped member *60* is made longer than the bow-shaped member *60'*. The two members are designed in this way because the member *60* is located as can be seen from Fig. 1 just below the box *A* in which the healds *M* for the initial shedding are located and the pointed end of the bow-shaped member *60* can therefore enter into the initial shed *b*. The lower bow-shaped member *60'* is located near the picking apex where the shed *b* is nearly zero. Consequently, the bow-shaped member *60'* finds in the beginning of the weaving operation no opening into which it can wedge itself. Only after the initial shed *b* is increased by the bow-shaped member *60* and the belt *54* associated therewith the shedding is increased far enough so that the lower bow-shaped member *60'* also enters the shed. If desired, the lower bow-shaped member *60* may be extended by a suitable shaped portion towards its rear in which case the belt *55* and the pulleys associated therewith may be omitted.

It will be understood that each of the elements described above, or two or more together, may also find a useful application in other types of circular weaving looms differing from the types described above.

While the invention has been illustrated and described as embodied in a circular weaving loom having a warp threads shedding operation device combined with the weft thread carrying device, it is not intended to be limited

to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be secured by Letters Patent is:

1. In a circular weaving loom, in combination, a plurality of healds to effect guiding and shedding of the warp threads, a box wherein said healds are annularly arranged in groups, a warp shedding device formed by a plurality of moving members which are mounted to rotate at the rear part of said healds so as to exert a pressure thereon to push them forwardly, a warp stop motion means connected to said shedding device for turning movement therewith and including a feeler formed by a bar and by an arm to which said bar is secured, said bar being formed with a threaded hole, a screw threadedly engaging said bar in said hole and formed with an axial bore, a rod extending through said bore, a roller loosely mounted on said rod and positioned so as to engage the rear ends of said healds, said roller having a height which enables it to engage all heald groups, a helical spring wound around said rod, a pin on said rod, a lever engaged by said pin and turnable on said bar of said feeler, said lever being adapted to close an electric loom stopping circuit, a second spring also wound around said rod and exerting a pressure on said pin and thus on said lever to maintain said roller against said healds, and a weft spool carrying device including a weft carrying carriage, a bent needle having a V-shaped cross section tapering toward the lower end of said needle to effect the guiding of the weft thread, and a shed spreader means for moving warp threads from an inner to an outer position at which the picking is effected.

2. In a loom as defined in claim 1, said healds each being formed by a rod provided with an extending portion of reduced cross section which terminates with a long, narrow eyelet the size of which corresponds to the thread count.

3. In a loom as defined in claim 1, said healds each being formed by a rod having an extending portion of reduced cross section ending with a straight and thin steel blade forming a side face which guides the warp thread in cooperation with the similar side face of the succeeding heald, and so on through an entire circle of healds.

4. In a loom as defined in claim 1, said carriage comprising a framework of magnetic material, two brackets mounted on said framework, two spindles mounted on said brackets so as to be able to rotate in their supports, two equal wheels of magnetic material keyed on said spindles, two equal toothed wheels mounted on said spindles, an electromagnetic roller able to support and to attract the carriage, a smaller wheel of magnetic material rotatably mounted on its spindle and positioned in the

upper part of said carriage in order to face said electromagnetic roller, an upper bow and a lower bow, both designed to be wedged between the warp threads and precisely the upper bow in advance in respect to the lower bow, in the movement direction, so that the lower bow may be wedged in only after the gradual increasing of the shed.

5. In a loom as defined in claim 4, said shed spreader means comprising two pinions respectively engaging said toothed wheels and being rotatable on their spindles, two pulleys respectively keyed to the latter, two rollers loosely mounted on their spindles, and two belts arranged on said pulleys and on said rollers so as to define two closed paths, whereby a gradual continuous spreading of the warp threads is performed upon rotation of said magnetic wheels.

6. In a loom as defined in claim 1, the moving members of said shedding device being in the form of star-shaped wheels which are turned so as to unwind on healds to exert a push thereon.

7. In a loom as defined in claim 1, said moving members of said shedding device being magnetized and operating by magnetic attraction on said healds to return the latter to their initial position.

8. In a loom as defined in claim 1, said healds being returned to their normal position by the resilience of the warp threads which exert a push on the healds.

9. In a loom as defined in claim 1, the lower part of said shed spreader means being formed by a suitably shaped and extending bow piece.

10. In a loom as defined in claim 1, said moving members being in the form of discs.

11. In a loom as defined in claim 1, and wherein a means for returning said healds to their initial position is formed by a plurality of springs respectively connected to said healds.

12. In a circular weaving loom, in combination, a main loom shaft; a first magnetic roller parallel to said main loom shaft, spaced therefrom and mounted for rotation about the same on the inside of the warp threads of the loom; a carriage; a second magnetic roller mounted on said carriage adjacent to said first magnetic roller to be attracted to and supported thereby for turning movement therewith about said main shaft, whereby said carriage turns with said second roller about said main shaft; and at least one substantially pointed member extending forwardly from said carriage in the direction of rotation thereof with said first roller to effect spreading of the warp threads.
